FOREIGN PATENT DOCUMENTS

CN 307235328 * 4/2022

Primary Examiner — T Chase Nelson*Assistant Examiner* — Kelly L Gross(74) *Attorney, Agent, or Firm* — Nitin Kaushik(57) **CLAIM**

The ornamental design for a disinfection box, as shown and described.

DESCRIPTION

FIG. 1 is a front perspective view of a disinfection box, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

1 Claim, 8 Drawing Sheets
